UNITED STATES PATENT OFFICE

HARRY SCHLESINGER, OF DES MOINES, IOWA, ASSIGNOR OF SEVENTY-FOUR ONE-HUNDRED-AND-EIGHTY-THIRDS TO ALFRED F. YOERG AND THIRTY-FIVE ONE-HUNDRED-AND-EIGHTY-THIRDS TO JACK GOLDBERG, BOTH OF DES MOINES, IOWA

HAT CLEANER AND DRIER

Application filed September 23, 1929, Serial No. 394,633. Renewed October 6, 1932.

More particularly, it is my object to provide a hat cleaner and drier in which an improved means is provided for driving a hat chuck and a blower device.

5 A further object is to provide in a machine of the character herein disclosed having an operating motor and a heater with controls for the motor and heater, a means for positively locking the controls against movement 10 to "on" position when the lid of the machine is in opened position.

15 A further object is to provide a sliding bar and link connection for throwing the machine out of operation when the lid is open, the lid engaging the link connection.

Another object is to provide a novel clutch construction, whereby the hat chuck may be thrown in and out of operation selectively.

20 Another object is to provide a wringer basket of the centrifugal type especially adapted to be associated with the hat chuck, whereby the cleaning fluid used in ties or other small articles may be extracted in the hat drying chamber of the machine.

25 Another object is to provide an improved type of control for a vertically movable hat block in the machine, whereby the hat block may be caused to assume any desired elevation.

30 Another object is to provide a novel holder for a glass jar or other receptacle to receive the cleaning fluid flowing from the cleaning chamber and drying chamber of the machine.

35 With these and other objects in view my invention consists in the construction, arrangement and combination of the various parts of my device, whereby the objects contemplated are attained, as hereinafter more fully 40 set forth, pointed out in my claims, and illustrated in the accompanying drawings, in which:

Figure 1 is a plan view of my improved type of hat cleaner and drier, parts being broken 45 away to show the construction.

Figure 2 is a left end elevation of the same.

Figure 3 is a sectional view on the line 3—3 of Figure 1.

Figure 4 is a sectional view on the line 4—4 50 of Figure 3.

Figure 5 is a bottom plan view of an extractor basket used in the machine.

Figure 6 is a sectional view on the line 6—6 of Figure 3.

55 Figure 7 is an enlarged detail view looking at a portion of Figure 6, as indicated by the arrow 7; and

Figure 8 is a plan view of a receptacle holder looking in the direction of the arrow 8 60 on Figure 3.

65 On the accompanying drawings I have used the reference numeral 10 to indicate supporting legs of my cleaner and drier. A top 12 is secured to the supporting legs 10 and suitable frame members and forms a table top. Extending downwardly from the top 12 is a 65 cleaning chamber 14.

A hub 16 is formed on the bottom of the chamber 14 and a sleeve 18 is vertically slidable through this hub. The sleeve 18 is also 70 guided by a rod 20 secured to a cross member 23 of the frame of the machine. A plug 22 is secured in the upper end of the sleeve 18 and terminates in a reduced pin 24 adapted to support a hat block 26. The hat block 26 is reversible so that the flat side thereof may be used in straw hats 28 as shown in Figure 75 3 is dotted lines.

A bumper spring 27 is mounted on the rod 20 below the sleeve 18. A clamp member 30 is secured to the sleeve 18 and a control lever 32 is in turn secured to the member 30. A handle 34 is provided for convenience of the operator in moving the lever 32 upwardly or downwardly as desired. The lever 32 extends between a stationary block 36 and an eccentric block 38 as best shown in Figure 7.

80 A spring 40 is anchored to the frame member 42 at one end and to the handle of the eccentric block 38 at its other end for normally causing the eccentric block to force the lever 32 against the stationary block 36 and thus hold the hat block 26 against downward movement. The handle 34 may be grasped 85 for pulling the lever 32 upwardly without manually releasing the eccentric block 38, but when it is desired to move the lever downwardly, the eccentric block must be manually released.

90 On the table top 12, I provide a cleaning 95 100

fluid receptacle 44 adapted to contain a cleaning fluid in an easily accessible position for using it in cleaning hats. A drain pipe 46 controlled by a drain valve 48 extends from 5 the receptacle 44 to the cleaning chamber 14.

Supported on the table top 12 is a drying chamber 50 having a hinge lid 52. A drain pipe 54 extends from the drying chamber 50 for discharging fluid therefrom into the neck 10 of a glass bottle or other suitable receptacle 56. A drain pipe 58 extends from the cleaning chamber 14 to the drain pipe 54.

As best shown in Figure 8, a holder for the bottle 56 is provided and consists of a stationary base plate 60 having a stationary shoulder 61 and a movable shoulder 63. The movable shoulder 63 is constrained toward engaging position with the receptacle 56 by means of the spring 65.

20 Within the drying chamber 50 is a hat chuck 62 fully described in my copending application. A clutch lever 64 is provided for actuating the hat chuck 62 and is engageable with a notched bar 66 for retaining the 25 chuck in any adjusted position. A spring 68 holds the clutch lever 64 in the notches of the bar 66.

The hat chuck 62 is different from the one shown in my copending application in that 30 the hat engaging members 70 are made considerably larger for better gripping the inside surface of the hat crown and they are perforated so that the circulating current of drying air through the drying chamber may 35 pass outwardly through them for more thoroughly drying the hat adjacent the hat engaging members.

The members 70 have their upper edges curved inwardly as clearly shown in the 40 drawings. This is so that they will not make a ring or bulge inside of the crown of the hat when expanded. The projections 71 on the members 70 are to support the hat.

A thermostatically controlled electric heating device, the casing of which is indicated by the reference numeral 72 is used for heating the drying air in the present machine. This heater is similar in construction to the one illustrated in my copending application 45 in which it is fully described.

The casing 72 is connected with a manifold 74 extending upwardly as indicated at 76 into the drying chamber 50. A switch 78 is provided for turning the heater in the casing 72 55 on or off, as desired. A manifold 80 is provided on the lid 52 and hinges with the lid. The manifold 80 connects with a manifold 82 which is in communication with a blower 84 by means of a tube 86.

60 The blower 84 is provided with a pulley 88, whereby the blower may be driven from a motor 90 by a belt 92. The belt 92 extends upwardly from both sides of the motor pulley and over a pair of idlers 94 and 96. The belt 65 then extends in opposite directions and

around the pulley 88 and a hat chuck pulley 98. Thus, the pulleys 88 and 98 are driven by one belt from the motor 90.

70 A disk 100 is secured to the hat chuck shaft 102, but the pulley 98 is loosely mounted thereon. A clutch member 104 is also loosely mounted on the shaft 102. A pair of clutch pins 106 are secured to the clutch member 104 and are adapted to extend through openings 108 in the disk 100 and into openings 110 in the hat chuck pulley 98 (see Figure 3).

75 Sockets 112 are provided in the disk 100 for the pins 106 to rest in when the clutch member 104 is withdrawn for rendering the hat chuck inoperative.

80 In connection with the hinge of the lid 52, I provide a link 114 to act as a seat for the lid when open. The link 114 is connected with a slideable bar 116 normally held in an upward position by a spring 118. The lower end of the bar 116 is provided with a foot 120 adapted to engage a latch member 122 when the lid is in closed position and to hold such member in a raised position. The latch member 122 is adapted to drop behind a lug 124 85 on a lever 126 (see Figure 2) when the lid 52 is opened and the weight thereof causes the bar 116 to move downwardly.

85 The lever 126 is connected by a rod 128 with a motor switch control 130. The lever 126 also offers an obstruction to a handle 132 on a valve plate 134 adapted to control the flow of air through the manifolds 80 and 82. By this construction, the motor 90 and the valve plate 134 cannot be moved to "on" position when the lid 52 is raised as the latch 122 prevents movement of the handle 132 to "on" position and a pin 136 on the control rod 130 prevents movement of the control rod 130 to "on" position as this pin engages the 90 rod 138. The "on" position of the motor control 130 is outwardly.

95 When the lid 52 is opened manually or because of an explosion in the drying chamber 50, the foot 120 of the bar 116 engages the lower end 138 of the lever 126 for pulling the switch 130 to "off" position and closing the valve plate 134.

100 In the case of an explosion, the violent opening movement of the lid 52 causes it to swing backwardly to closed position after shutting off the motor control and the air valve so that it will smother any flames in the drying chamber.

105 In connection with the manifold 74, I provide a door-like valve 140 controlled by a rod 142 and over-center spring 144. This valve may be moved to the dotted line position shown in Figure 4, whereby fresh air instead of air through the heater 72 may be 110 used in the drying process if desired.

115 In my copending application I illustrated a safety lever to prevent opening of the valve plate 134 and prevent starting of the motor 90 except when the clutch lever 64 was moved 120

from its smallest adjusted position. This was for the purpose of preventing operation of the motor except when the hat chuck was expanded, but I have found such a feature 5 unnecessary, as the hat chuck can be expanded while in rotation, but cannot be contracted. This is because of a contracting action of the clutch lever tending to rotate the hat chuck faster than it already is rotating and I find that sufficient pressure can be exerted on the lever 64 in trying to contract the hat chuck which will lift the machine, but will not move the lever 64 relative to the machine. This is a desirable feature, 10 as while in rotation, it is impossible to contract the hat chuck and thereby loosen the hat so that it will fly off the chuck.

In order to prevent hats from being expanded too much, especially ladies' hats having brims of irregular shape, a flat metal band 20 may be placed around the hat and the hat expanded by the chuck members 70 against this band. It would be preferable, of course, to have several bands of different sizes to fit 25 various sizes of hats.

In connection with the hat chuck I provide an extractor basket 146 having a downwardly extending flange 148 of the proper shape to fit the hat engaging member 70. The 30 flange 148 is felt lined as indicated at 150. This basket may be placed on the hat chuck and the hat chuck expanded for tightly engaging the flange 148 (the felt 150 being between the flange and the hat engaging members). The flange 148 rests on the members 35 71 and on top of the members 70 or may be arranged to rest on either alone. Thus, ties and other small articles after being washed out in a cleaning fluid may be placed in the 40 extractor basket 146 for extracting the fluid therefrom which will run into the receptacle 56.

The valve plate 134 may be open for allowing the circulation of air for completely drying 45 and deodorizing the articles in the basket 146.

Some changes may be made in the construction and arrangement of the parts of my device without departing from the real spirit 50 and purpose of my invention, and it is my intention to cover by my claims, any modified forms of structure or use of mechanical equivalents, which may be reasonably included within their scope.

55 I claim as my invention:

1. Hat drying mechanism comprising a drying chamber, a cover therefor, a hat support in said chamber, power means for rotating said support, control means for said power means, and mechanism for moving said control means to inoperative position when the cover is opened, said mechanism comprising a link pivotally supported at one end, a bar pivoted to the other end thereof and having a portion slidably mounted,

spring means to hold the bar in one position and means operatively connected with the control means and adapted to be engaged by the bar when moved against the action of the spring to throw the control means to "off" 70 position.

2. Hat drying mechanism comprising a drying chamber, a cover therefor, a hat support in said chamber, power means for rotating said support, control means for said power means, and mechanism for moving said control means to inoperative position when the cover is opened, said mechanism comprising a link pivotally supported at one 75 end, a bar pivoted to the other end thereof and having a portion slidably mounted, spring means to hold the bar in one position, a lever, a link connecting the lever with the control means, said bar being arranged to engage the lever and move the link and control means to "off" position when the bar is moved against the action of the spring.

3. Hat drying mechanism comprising a drying chamber, a cover therefor, means for supplying heated air thereto, a control valve 90 included in such means, and mechanism for closing said valve in the event said cover is opened, said mechanism comprising a link pivotally supported at one end, a bar pivoted to the other end thereof and having a portion slidably mounted, spring means 95 to hold the bar in one position and a lever adapted to engage said valve and move it to closed position when the bar is moved against the action of the spring.

4. Hat drying mechanism comprising a drying chamber, a hat chuck therein, fan means for forcing air through said chamber, a motor for operating said fan means and for rotating said chuck, a control for energizing and de-energizing said motor, a valve for controlling the flow of such air, a lid for said chamber and means to normally prevent movement of said control for said motor to energizing position except when said lid is closed, said last means also operating to instantly move said valve to closed position when said lid is opened.

HARRY SCHLESINGER.
